UNITED STATES PATENT OFFICE.

CYRUS A. WHITTAKER, OF FREEBURG, ILLINOIS.

DESIGN FOR A BADGE OR BUTTON.

No. 88,532.

Specification for Design.

Patented April 23, 1907.

Application filed February 19, 1907. Serial No. 358,298. Term of patent 7 years.

To all whom it may concern:

Be it known that I, CYRUS A. WHITTAKER, a citizen of the United States, and a resident of Freeburg, Illinois, have invented a certain new and original Design for Badges or Buttons, of which the following is a specification, reference being had to the accompanying drawings, forming a part hereof.

Figure 1 is a plan or face view of a badge or button embodying my new design; Fig. 2

is an edge view of a badge or button, and showing my new design.

I claim:

The ornamental design for a badge or button, as shown.

CYRUS A. WHITTAKER.

Witnesses:

C. C. DALRYMPLE,
C. H. KETTLER.
